MARTIN J. WALSH, OF NEW YORK, N. Y.

FIRE-EXTINGUISHING SYSTEM.

1,169,210.

Specification of Letters Patent. Patented Jan. 25, 1916.

Application filed March 15, 1915. Serial No. 14,394.

To all whom it may concern:

Be it known that I, MARTIN J. WALSH, a citizen of the United States, and a resident of the borough of Manhattan, city, county, and State of New York, have invented certain new and useful Improvements in Fire-Extinguishing Systems, of which the following is a specification.

My invention relates to a fire extinguishing system which contemplates primarily the utilization of sand or other finely divided noncombustible substances to extinguish the fire, the system being automatically brought into operation by the presence 10 of excessive heat due to such fire.

It is a well known fact that in the case of highly inflammable material the sprinkler devices now in use, wherein water is automatically liberated from pipes supported 20 from the ceiling, the water will frequently aid in spreading and distributing the area of the conflagration, this being particularly true in establishments where chemicals, oils, naphtha, gasolene, benzin and other highly 25 inflammable liquids or chemicals are employed, such as in cleaning and dyeing establishments, garages, laboratories, paint-shops, etc. By my present invention this vital objection to the water sprinkler systems is overcome and it will be obvious also 30 that by employing as the extinguishing medium a finely divided noncombustible material, such as sand, the loss through the ruination of goods, wares and merchandise 35 so frequently incurred through the use of the water sprinkler systems is, in most cases, wholly avoided.

In the accompanying drawings, Figure 1 represents a perspective view of a portion of a room or loft equipped with my invention; 40 Fig. 2 represents a plan view of a section of the grating and the wire mesh upon which the fusible support and the sand or other finely divided noncombustible material are maintained, and Fig. 3 represents a cross-section taken on line 3—3 of Fig. 2. In these several figures like reference letters represent like parts.

1 represents the ceiling of the loft or room 50 equipped with my system; 2 represents floor beams which are usual to such ceilings and whereby the ceilings are supported; 3 represents a grating supported from said ceiling as by supporting rods 7 which at their 55 upper ends are secured to and suspended

from the floor beams 2, while at their lower ends these rods are in holding engagement with the grating 3 as indicated at 7a.

4 represents a wire mesh, supported upon said grating 3; 5 represents a layer or sheet 60 of fusible material which is super-imposed upon or supported by the wire mesh 4; 6 represents a layer of finely divided noncombustible material, such as sand, which in turn is supported by the said fusible material 5, in proximity to the ceiling.

For the purpose of illustrating the operation of my invention, it will be assumed that a fire has started in the room or loft illustrated in Fig. 1. Owing to excessive heat 70 rising toward the ceiling the material 5 which is highly sensitive to heat melts or fuses and the finely divided noncombustible material 6 resting thereon is liberated and drops through the meshes of the wire screen 75 4 and the grating 3 and upon the fire, thus smothering it and preventing the further spread thereof.

It will be understood, of course, that the grating, wire mesh and fusible material may 80 be arranged in panels to suit individual requirements and that they may be supported in any desired or convenient manner other than as indicated by way of example in Fig. 1 of the drawings. It will further be understood that the layer of finely divided noncombustible material may be supplied in any 85 desirable manner, as for instance by blowing in the sand or by rendering the panels movable to permit of access to adjacent panels, 90 or by suitably spacing the panels apart to permit of access thereto for the purpose of filling in or inspecting the finely divided noncombustible material. Instead of the 95 grating 3 and the wire screen 4, suitably perforated sheets of tin or other mediums of support may be employed to sustain the fusible material and the finely divided noncombustible material in their elevated position and said materials may moreover be maintained in proximity to the ceiling by means 100 other than supports depending therefrom, as for instance by side brackets or standards rising from the floor over which the fusible material of my system is provided.

It will appear from the foregoing description that the gist and spirit of my invention embraces the utilization of a finely divided noncombustible material maintained in position in proximity to the ceiling by a support 110

which will fuse under the action of excessive heat, the fusing of said support resulting in liberating said finely divided noncombustible material to permit the same to drop by gravity upon the floor below.

I claim:

1. A fire extinguishing system comprising a fusible support, finely divided noncombustible material located upon said support, and means for maintaining said support in an elevated position, whereby the fusing of said support from heat beneath it will permit said material to drop by gravity.
2. A fire extinguishing system comprising a fusible support, finely divided noncombustible material maintained in an elevated position by said support, whereby the fusing of said support from heat beneath it will permit said material to drop by gravity.
3. A fire extinguishing system comprising a wire mesh, means for maintaining said wire mesh in an elevated position, a fusible support sustained by said wire mesh, and

finely divided noncombustible material located upon said support.

25

4. A fire extinguishing system comprising a fusible support, finely divided noncombustible material maintained upon said fusible support and means for maintaining said support in an elevated position adjacent the ceiling.

5. A fire extinguishing system comprising a perforated support in an elevated position, a fusible support sustained by said perforated support and finely divided noncombustible material maintained in an elevated position by said perforated and fusible supports.

35

In testimony whereof, I have hereunto set my hand in the presence of two subscribing witnesses.

40

MARTIN J. WALSH.
